UNITED STATES PATENT OFFICE.

WILLARD IRVING TWOMBLY, OF NEW YORK, N. Y., ASSIGNOR TO TWOMBLY MOTORS COMPANY, OF NEW YORK, N. Y., A CORPORATION OF NEW YORK.

INTERNAL-COMBUSTION ENGINE.

1,117,464.

Specification of Letters Patent. Patented Nov. 17, 1914.

Application filed September 19, 1911. Serial No. 850,194.

To all whom it may concern:

Be it known that I, WILLARD IRVING TWOMBLY, a citizen of the United States, residing in the borough of Manhattan, in the city, county, and State of New York, have invented new and useful Improvements in Internal-Combustion Engines, of which the following is a specification.

This invention relates to internal combustion engines, in which a series of radially projecting cylinders are circumferentially disposed around a shaft having a crank, pistons connected to the crank pin working in the respective cylinders.

15 It is the primary object of the invention to improve the general engine construction, and provide improved means to control the taking in of a charge of fuel to the cylinders, the utilization of the same, and the 20 exhausting of the burnt gases from the cylinders.

It is a further object of the invention to provide the cylinder with a normally closed valve to control the exhaust therefrom, with 25 a piston connected to the pin of the crank shaft to work in said cylinder having a normally closed valve to control the passage of the fuel to the cylinder, and to provide means to open said valves, comprising an 30 inlet-valve operating-cam on the crank pin of the shaft and an exhaust-valve operating-cam on the crank shaft, said cams being so constructed that the inlet valve will be opened upon alternate reciprocations of the 35 piston or during the suction strokes, and the exhaust valve will be opened upon alternate reciprocations of the piston and alternately with the opening of the inlet valve or during the exhaust strokes.

40 It is another object of the invention to provide means to adjust the full intake-valve operating-cam on the crank pin to control the volume and compression of the fuel in the cylinders, and thereby regulate the 45 power and speed of the engine.

Another object of the invention relates to the connection of the pistons to the crank pin of the shaft, comprising a revolving member on the crank pin, and connecting 50 rods connected to the pistons and said revolving member, one of the rods being rigidly connected to the revolving member to maintain said member in proper position on the crank pin with relation to the connecting rods of the other pistons.

Further objects and advantages will hereinafter appear.

As a preface to a description of the construction and operation of the engine, I wish to state, that while the engine is illustrated as being of the rotary type operating on the four cycle principle; that is, the pistons and cylinders rotate about a fixed crank shaft or axes, it is to be understood that the engine may be constructed so that the crank shaft revolves and the cylinders are stationary; and instead of the cylinders being circumferentially disposed around the crank shaft they may be stationary to extend along the shaft and a separate cam provided for each of the valves.

In the drawings accompanying and forming a part of this specification, Figure 1 is a sectional side elevation of my improved engine taken substantially through the engine on a line corresponding with the line A—A in Fig. 8. Fig. 2 is an enlarged vertical sectional side elevation taken through the middle of one of the cylinders, its piston mechanism and the casing, part of the latter being broken away, and illustrating the lubricating means. Fig. 3 is a sectional end elevation taken through the cylinders, and is in the nature of a diagrammatic view to illustrate the positions of the pistons in the cylinders and the positions of the valves at a certain point in the rotation of the engine. Fig. 4 is a view looking at the front of the intake and exhaust valve-operating cams, illustrating the positions of the cam-follower shoes in the respective cam grooves when the valves are in the positions illustrated in Fig. 3. Fig. 5 is a front elevation of one of a pair of rings by means of which the connecting rods of the pistons are connected to a revolving member on the crank pin. Fig. 6 is a sectional plan view of one of the cam-follower shoes. Fig. 7 is a view looking at the top of one of the cylinders and a portion of the casing, part of the latter being broken away to illustrate the position of the exhaust valve operating-cam on the shaft, and also showing the manner of operating the magneto from the engine. Fig. 8 is a front elevation of the intake-valve operating-cam and the means to adjust said cam on the crank pin to control the opening and closing of the intake valves in the pistons to regulate the power and speed of the engine, said view showing the

cam in full lines in normal position on the crank pin, and in dotted lines in one of the positions to which it may be adjusted. Fig. 9 is a sectional side elevation of the parts shown in Fig. 8. Fig. 10 is a detail view of one of the gudgeon pins upon which the connecting rods are mounted to connect them to the pistons. Fig. 11 is a sectional side elevation illustrating the manner of securing the cylinders to the casing.

Similar characters of reference designate like parts throughout the different views of the drawings.

In the embodiment of my invention illustrated in the drawings, I have shown the engine to be adapted as the motive power for propelling an aeroplane, and comprising a casing 1, which is in the nature of a fuel chamber, mounted by ball bearings, 3, 4 on a fixed hollow shaft 5 having a crank 6 to rotate about either a horizontal or vertical axis. The casing is provided with a series of circumferentially-disposed openings in which engage cylinders 7 to project radially from the casing, said cylinders having laterally projecting flanges to abut against the casing and secured thereto by clamping members 8 and bolts, the clamping members having a cut out portion so that they will engage over the cylinder flanges. The cylinders may also be provided with laterally-projecting flanges or fins 8' whereby to aid in the air cooling thereof. The casing is connected to the source of fuel supply, such as a carburetor, (not shown,) by means of a pipe 9 connected to the shaft 5.

The shaft is supported by a bracket 10 having a sleeve portion in which the shaft engages, one end of the sleeve abutting against a shoulder on the shaft and a pair of lock nuts 11 drawing and locking the shaft shoulder firmly up against the bracket and preventing any axial movement of the shaft. The engine is fixed in position in the fuselage of an aeroplane, or the frame of a motor vehicle by brackets 12 fixed to laterally-projecting portions of the bracket 10.

To maintain the bearing 4 in position I provide an annular cap 13 connected to the casing by bolts 14 to rotate therewith, a thrust bearing 15 being confined between the bearing 4 and the cap 13 to take up any forward pull or thrust of the engine when a propeller 16 is secured thereto and the engine utilized as the motive power for an aeroplane.

Pistons 17 for the respective cylinders having the usual packing rings and oil grooves, are connected to the crank pin 6 to rotate with the cylinders about said pin as an axis, and during the rotation of the cylinders reciprocating therein. The connections of the pistons to the crank pin con-

sist of tubular rods 18 connected at one end to heads 19 whereby they are pivotally mounted upon gudgeon pins 20 secured in hangers 21 having a screw threaded engagement within the pistons with removable valve seats 22 in the piston heads, the said valve seats having lateral annular flanges to engage with the top of the pistons. The other ends of the rods 17 have a screw threaded engagement with members 23 to connect them to a revolving member on the crank pin. This revolving member consists of a pair of bearings 24, 24, (in the present instance shown as ball bearings,) rings 25 surrounding said bearings and each having an inwardly extending annular flange with a series of equidistantly spaced and circumferentially disposed holes, one hole in each ring flange being polygonal in shape for a purpose to be hereinafter described. All of the rods 17, with the exception of one, are connected to the revolving member by gudgeon pins 26 engaging in the openings in the ring flanges and upon which the members 23 are pivotally mounted. The member 23 of one of the rods 17 has lateral projections polygonal in shape to engage in the polygonal holes in the ring flanges to rigidly connect said rod to the bearings 24 and thereby prevent movement of one bearing relative to the other on the crank pin, as clearly shown in Fig. 5. It will be noted that one portion of the crank pin has a reduced diameter, as at 27. This is to permit of the slipping of the bearings 24 over the offset portion of the crank when placing on the crank pin, and the maintaining of the bearings to a minimum size. A bushing 28 is provided for one of the bearings (at the left of Fig. 1) consisting of a pair of semi-circular sections.

The admission of fuel from the fuel chamber 1 to the cylinders is controlled by mechanically operated valve mechanism in the respective pistons, comprising puppet valves 29 the stems of which are slidably supported in the valve seats 22, headed studs 30 passing through and having a screw threaded engagement with the valve stems and locked in position by nuts 31, coiled springs 32 confined between the heads of the valve studs and seats normally maintaining the valves seated. The valves are operated by means of a cam 33, common to all of the valves, mounted upon the wrist pin by a bracket 34 fixed to the offset of the crank, said cam comprising a disk having a pair of concentric and intersecting grooves in the face thereof, the outer groove having an eccentric or raised portion for approximately 180 degrees. Cam-followers comprising rods 35 are slidably mounted in the heads 19 and bushings 36, bushings 36', in the hollow rods 18, being secured to and moving with the rods to prevent distorting

of the latter. The rods are provided with a laterally-extending portion 37 projecting through slots 38 in the rods 18 and connecting members 23, with shoes 39 pivotally carried thereon to engage in the cam grooves. The heads of the valve studs are provided with projecting portions 30' to extend into openings in the connecting-rod heads 19 and pins 20 to be engaged by the ends of the rods 35. (Fig. 1).

The cam-follower shoes are so constructed that as the engine completes one revolution they will be readily switched through the intersecting portion of the cam grooves from the outer to engage in the inner cam groove during the succeeding revolution, and again be switched into the outer groove upon the subsequent revolution of the engine, and for this purpose are constructed as shown in Fig. 6, comprising a pair of connected plates with the cam engaging edges substantially flat, while the upper edges are convex, the both ends being pointed or wedge shaped to guide and facilitate the switching thereof through the intersecting portion of the cam grooves.

The exhaust of the burnt gases from the cylinders is controlled by mechanically operated valve mechanism in the cylinders, comprising valves 40 the stems of which are slidably mounted in removable valve seats 41 in the cylinder heads. The operation of the exhaust valves is controlled by a cam 42 keyed to the projecting end 43 of the crank shaft and held thereon by a nut 43', said nut also serving to prevent axial movement of the casing 1 on the shaft 5. The cam 42 is similar to the fuel-inlet valve-operating cam 33; that is, it consists of a disk having a pair of concentric and intersecting grooves or raceway in the face thereof with the outer groove having an eccentric or raised portion for approximately 180 degrees. The fuel-intake and exhaust valve operating cams are so set that the eccentric portions are substantially diametrically opposite. The cam 42 is inclosed in a chamber formed at the end of the casing 1 by an annular member 44 and a releasable plate 45 held in place by means of tie rods 2 passing through the casing 1. This chamber is adapted to be filled with a suitable lubricant. When the engine is to be utilized as the motive power for an aeroplane the propeller 16 is fixed to the plate 45. However, when used as the motive power in a motor vehicle to rotate on a horizontal axis the vehicle drive shaft is connected directly to said plate 45, but when the motor is mounted in the vehicle frame to rotate on a vertical axis a bevel pinion is fixed to the plate to mesh with a corresponding pinion on the drive shaft of the vehicle. Fulcrumed to studs 46, fixed in arms 47 projecting laterally from the cylinders are rockers 48, connected at one end to the stems

of the exhaust valves and the other ends to rods 49 slidably mounted in the arms 47 and with their free ends engaging in tappets 50 slidably mounted in bushings 51 screw threaded into the annular member 44, the lower end of said rods resting upon balls 52 in said tappets. Fixed in and projecting at right angles to the tappets are studs 53 on which shoes 54 (similar to the shoes 39) are pivotally supported to engage in the race-way in the cam 42. The valves are normally maintained closed by springs 55 coiled about the rods 49 and confined between the arms 47 and collars 56 on the rods.

To oil the pistons and engine bearings, I provide an oil reservoir or distributor at one end of the casing 1, consisting of an annular recess 57 the outer end of which is closed by the cap 13. Oil is fed to said reservoir through a duct 58 communicating with an annular recess or duct 59 in the cap to which is connected a duct 60 passing through the shaft and connected to an oil tank. (Not shown). The oil distributor 57 is connected with the cylinders by sectional ducts 61 connected by a coupling 62. Suitable check valves are provided in said ducts to prevent a back flow of the oil, each consisting of a ball-seat in the coupling 62, a ball 63 and a spring 64 to normally seat the ball. Suitable means is also provided to regulate the flow of oil to the cylinders, and is shown as comprising needle valves 65 in the ducts 61. As the engine rotates the oil from the distributor 57 is thrown outwardly by centrifugal action opening the check valves in the ducts 61 and causing the oil to flow to the walls of the cylinders. As the engine is stopped or comes to rest, the balls will be seated by the springs 64 and shut off the flow of oil. Branching out from the annular recess 59 in the cap 13 is a duct 66 leading through the shaft, the crank, and the crank pin, with ducts branching out therefrom and leading to the bearings, as clearly shown in Fig. 2. Any oil that oozes out from the chamber 44 into the casing or fuel chamber 1, or drips from the bearings, will be thrown outwardly through the valves in the pistons by centrifugal action as the engine rotates thereby serving as an additional means to oil said valve mechanism and the pistons.

The speed and power of the engine are controlled by the volume and compression of fuel in the cylinders, and for this purpose I so mount the inlet-valve operating-cam 33 upon the wrist pin to have rotative adjustment thereon. To adjust the cam 33 I provide a sleeve 67 rotatably mounted in the shaft 5 and connected to the cam by a link 68. A lever 69 fixed to said sleeve projects through a slot 70 in the shaft and to which lever is connected an operating lever to advance or retard the cam. The connection of

the cam and its adjusting means may be such that the maximum amount of the adjustment of the cam will be approximately 90 degrees or one quarter of a revolution, 5 whereby when adjusted to its limit of adjustment the inlet valve for a cylinder will not be opened until the piston has made approximately one-half of the initial movement of its suction stroke, and will not be closed until it has traveled approximately 10 one-half of the initial movement of its fuel compression stroke, a portion of the charge of fuel previously taken into a cylinder being forced out of the cylinder and back into the fuel chamber 1, thus supplying only a 15 portion of a charge to a cylinder, and as this will be under low compression and burn slowly the engine will not develop its maximum power and consequently revolve at a low speed. When the cam is mounted for 20 adjustment on the crank pin the bracket 34 may be dispensed with; or the bracket may be provided with segmental slots; and headed studs fixed in the cam engage and work 25 in said slots.

As a preface to a description of the operation of my improved engine, I wish to say that for the purpose of illustration I have shown the engine as being provided with 30 seven cylinders, although a less number may be employed and the engine work efficiently, and for the purpose of clearness in describing the operation the cylinders have been indicated by the characters *a*, *b*, *c*, *d*, *e*, *f* 35 and *g*, respectively, (Fig. 3) which is the order in which combustion will take place in the cylinders, the engine revolving anti-clockwise in the direction indicated by the arrow, it being understood that this view is 40 taken looking at the rear of the engine. Furthermore, the engine is preferably operated on the four-cycle principle; that is, suction or admission of fuel, compression of fuel, combustion or power stroke, and the 45 exhausting of the burnt gases. This gives one power stroke for each cylinder every two revolutions of the engine.

The centrifugal action as the engine revolves, and the vacuum created during the 50 fuel compression and exhaust strokes of the pistons, will draw in a charge of fuel to the casing 1 through the hollow shaft and pipe 9 connected to the source of fuel supply, and as the pistons commence their suction strokes 55 and the inlet valves are opened, the fuel will enter the cylinders and be thrown outwardly toward the cylinder heads and packed therein, so to speak, through the action of centrifugal force.

60 Assuming the cylinders and pistons to be in the positions indicated in Fig. 3, combustion taking place and a power stroke being imparted to the piston in the cylinder *g*. Both the inlet and outlet exhaust valves are 65 closed in cylinder *a* and a charge of fuel

compressed therein about to be ignited; both of the valves are closed in cylinder *b* and a charge of fuel being compressed therein; the inlet valve in the piston in cylinder *c* is open and the piston approaching the end of its suction stroke, while the inlet valve in the piston in cylinder *d* is open and is commencing its suction stroke. The exhaust valve in cylinder *e* is open and the piston is approaching the end of its exhaust stroke, 70 while the exhaust valve in the cylinder *f* is open and the piston is beginning its exhaust stroke. In this position of the cylinders and pistons the shoes 54 of the cam-followers for the exhaust-valve operating-cam 42 will approximately assume the positions in the cam raceway indicated in Fig. 4, and the shoes 39 of the cam-followers for the inlet-valve operating-cam 33 will be substantially in the positions in the cam raceway 75 indicated in Fig. 4.

During 180 degrees of revolution of the engine in the direction of the arrow, the pistons and cylinders being substantially in the positions shown in Fig. 3 as already 80 stated, combustion will take place and a power stroke imparted to the piston in cylinder *a*, the piston in cylinder *e* will have completed its exhaust stroke and approach the end of its suction stroke, the piston in cylinder *b* will complete its compression stroke 85 and a power stroke imparted thereto, the burnt gases will be exhausted from the cylinder *f* and the piston commence its suction stroke, the piston will complete its suction 90 stroke and approach the end of its compression stroke in cylinder *c*, the piston will complete its power stroke and commence exhausting the burnt gases from cylinder *g*, and the piston in cylinder *d* will 95 complete its suction stroke and commence its fuel-compression stroke. During the succeeding 180 degrees of revolution of the engine, the burnt gases will be exhausted from cylinder *a*, the piston in cylinder *e* will complete its suction stroke and commence its fuel-compression stroke, the piston in cylinder *b* will complete its power stroke and commence exhausting the burnt gases from the cylinder, the piston in cylinder *f* will 100 complete its suction stroke and commence the compression of said charge, piston in cylinder *c* will complete its compression stroke and a power stroke being imparted thereto, the burnt gases will be exhausted 105 from and the piston begin its suction stroke in cylinder *g*, while the piston in cylinder *d* has completed its compression stroke and a power stroke is being imparted thereto. The pistons and cylinders are now again 110 substantially in the positions shown in Fig. 3 with the exception that the piston in the cylinder *a* is at the end of the exhaust stroke and the inlet valve in the piston is about to be opened, both valves are closed in the cyl- 115 120 125 130

inders *e* and *f* and compression of fuel taking place therein, the exhaust valve is opened in cylinder *b* and the burnt gases being exhausted therefrom, both valves are 5 closed in the cylinders *c* and *d* and a power stroke being imparted to the respective pistons, and the inlet valve in the piston in cylinder *g* is open and a charge of fuel entering the same. During the next cycle or 10 succeeding 180 degrees of revolution of the engine the valve in the piston in cylinder *a* will be opened and a charge of fuel sucked therein, the piston in cylinder *e* will complete its compression stroke and the combustion 15 of fuel take place therein the piston approaching the end of its power stroke, the piston in cylinder *b* will complete its exhaust stroke and commence its suction stroke, the piston in cylinder *f* will complete 20 its compression stroke, the charge ignited in said cylinder and a power stroke imparted thereto, the piston in cylinder *c* will complete its power stroke and approach the end of its exhaust stroke, the piston in 25 cylinder *g* will complete its suction stroke and commence its fuel-compression stroke, while the piston in cylinder *d* will complete its power stroke and begin to exhaust the burnt gases from said cylinder. During 30 the succeeding 180 degrees of revolution of the engine, the charge of fuel admitted to cylinder *a*, during the preceding cycle will be compressed, the piston in cylinder *e* will complete its power stroke and approach 35 the end of its exhaust stroke, the piston in cylinder *b* will complete its suction stroke and commence to compress the charge of fuel, combustion is taking place in cylinder *f*, the piston completing its power stroke 40 and commencing to exhaust the burnt gases from the cylinder, the piston in cylinder *c* will complete its exhaust stroke and commence its suction stroke, the piston in cylinder *g* will complete its compression stroke, 45 combustion taking place therein and a power stroke imparted to the piston, while the piston in cylinder *d* will complete its exhaust stroke and begin its suction stroke. The pistons, cylinders and valve mechanism 50 are now again in the positions illustrated in Fig. 3 when the cycle of operations will be repeated.

The inlet-valve and exhaust-valve operating cams are so located upon the crank pin 55 and shaft that the dwell or eccentric portions of said cams will come diametrically opposite to each other, as clearly shown in Fig. 4. It will be noted that the shoes 39 of the cam-followers of the inlet-valve operating-cam 33 engage in the outer groove of 60 the raceway during the latter portion of the exhaust stroke, the entire suction stroke and the initial portion of the compression stroke of the pistons, or one revolution, and during 65 approximately 180 degrees of said revolu-

tion, or the suction stroke, engage with the eccentric portion of the cam and impart movement to the valve-opening rods 35 whereby said rods engage with and maintain the inlet valves open, and that they are 70 so constructed as to be readily switched through the intersecting portion of the raceway in the cam to engage in the inner groove during the succeeding revolution or the latter portion of the compression stroke, the 75 entire power stroke and the initial portion of the exhaust stroke of the pistons with no movement imparted to the valve-operating rods 35 and the valves in the pistons maintained closed by the springs 32. It will also 80 be noted that the shoes 54 of the cam-followers for the exhaust-valve operating-cam 42 engage in the outer groove of said cam during the latter portion of the power stroke, the entire exhaust stroke and the initial portion 85 of the suction stroke of the pistons, and will engage with the eccentric portion of the cam during approximately 180 degrees of revolution of the engine, or during the exhaust stroke of the piston, imparting movement to the exhaust-valve operating-rods 49 to open the exhaust valves, the shoes being switched through the intersecting portion of the cam raceway to the inner groove to engage 90 therein during the latter portion of the 95 suction stroke, the enter compression stroke, and the initial portion of the power stroke of the pistons with no movement imparted to the valve-operating rods 49 and the exhaust valves being maintained closed by the 100 springs 55, when the shoes are again switched through the intersecting portion of the cam raceway to the outer groove.

Ports 75 are provided in the walls of the cylinders at diametrically opposite sides, 105 preferably in the front and rear sides of the cylinders; that is, in the sides in and opposite the direction of rotation of the engine. These ports are normally covered by the pistons during the fuel-compression and 110 exhaust strokes, and as the pistons approach the end of their power strokes serve as auxiliary exhaust ports to relieve the cylinders of any high pressures of combustion. These ports are also uncovered by the pistons at 115 the end of the suction stroke and any vacuum created in the cylinders, which may be caused by the throttling of the fuel supply to the engine, pure air will enter the ports to supply this vacuum at atmospheric pressure. 120

The charge of fuel is ignited by the sparking terminal of an igniting mechanism carried by a plug 76 secured in the head of each of the cylinders. The ignition mechanism 125 consists of an annular ring 77 of insulating material fixed to rotate with the engine and having seven sections (one for each cylinder) of conducting material 78 fixed thereto, the said ring constituting a commutator. 130

The respective sections 78 of the commutator ring are connected to the spark plugs 76 by conducting wires 79 with the current grounded in the cylinders. A brush or contact-maker 80 of suitable conducting material is secured to a post of insulating material 81 fixed to the lateral flanges of the shaft-supporting bracket 10 and is connected to the source of current, such as a magneto, shown in a general way at M, Fig. 7, by a conducting wire 82, and which magneto is operated from a gear 83 fixed to the cap 13. The commutator sections 78 are each provided with a resilient contact-making finger (Fig. 7) to contact with the contact-maker 80 as the engine revolves. The spark plugs of the respective cylinders are successively connected to the commutator sections 78 in the order of combustion in the cylinders; that is, in the order *a, b, c, d, e, f* and *g*, as shown in Fig. 3.

Having thus described my invention, I claim:

1. In an internal combustion engine, the combination of a crank shaft; a combined fuel chamber and crank case; a cylinder fixed to the case; a piston to work in the cylinder connected to the crank shaft; an inlet valve in the piston to control the charge of fuel from the fuel chamber to the cylinder; and a cam on the crank pin to open the valve upon alternate reciprocations of the piston.

2. In an internal combustion engine, the combination of a fuel chamber, a combustion chamber, an exhaust valve for said latter chamber, a piston to work in the combustion chamber, and a mechanically-operated inlet valve in the piston to control the passage of fuel from the fuel chamber to the combustion chamber, and means to adjust said inlet-valve operating mechanism at will to vary the time at which the inlet valve is opened and closed to regulate the volume and compression of fuel in the combustion chamber.

3. In an internal combustion engine, the combination of a crank shaft; a combined fuel chamber and crank case; a cylinder fixed to the case; an exhaust valve for the cylinder; a piston to work in the cylinder connected to the crank shaft; an inlet valve in the piston to control the charge of fuel from the fuel chamber to the cylinder; a cam on the crank pin; and means carried by the piston and crank connection operable by the cam to engage with and open the valve in the piston upon alternate reciprocations thereof.

4. In an internal combustion engine, the combination of a crank shaft; a combined fuel chamber and crank case; a cylinder fixed to the case; a mechanically operated valve in the cylinder to control the exhaust therefrom; a piston connected to the crank shaft to work in the cylinder; a spring

closed valve in the piston to control the charge of fuel from the fuel chamber to the cylinder; and a cam on the crank pin to open the valve in the piston against the action of the spring upon alternate reciprocations thereof.

5. In an internal combustion engine, the combination of a fuel chamber, a combustion chamber, an exhaust valve for said latter chamber, a piston to operate in the combustion chamber, an inlet valve in the piston to open and shut off communication between said chambers, a cam to operate the inlet valve, and means to adjust the cam to vary the time at which the inlet valve is closed during the compression stroke of the piston.

6. In an internal combustion engine, the combination of a crank shaft, a fuel chamber, a combustion chamber, an exhaust valve for said latter chamber, a piston connected to the crank-shaft to work in the combustion chamber, an inlet valve in the piston to open and shut off communication between said chambers, a cam on the crank shaft to operate the inlet valve upon alternate reciprocations of the pistons, and means to adjust the cam to vary the time at which the inlet valve is opened and closed during the reciprocation of the piston.

7. In an internal combustion engine, the combination of a crank shaft, a series of cylinders mounted to rotate about said shaft, pistons working in said cylinders, a fuel chamber common to all of said cylinders, spring closed inlet valves in the respective pistons to control the passage of fuel from the fuel chamber to the cylinders, and a cam on the crank shaft to open the inlet valves upon alternate revolutions of the cylinders or alternate reciprocations of the pistons.

8. In an internal combustion engine, the combination with a fixed crank shaft, of a series of cylinders rotatably mounted on said shaft; pistons working in said cylinders connected to the crank pin; a fuel chamber common to all of said cylinders; spring closed inlet valves in the pistons to control the passage of fuel from the fuel chamber to the cylinders; a cam on the crank pin of the shaft common to all of the piston valves; and cam followers carried by the piston and crank connections to engage with and open the inlet valves upon alternate revolutions of the cylinders.

9. In an internal combustion engine, the combination of a crank shaft, a series of cylinders and coöperating pistons rotatable about said shaft, a fuel chamber common to all of said cylinders, inlet valves in the pistons to control the passage of fuel from the fuel chamber to the cylinders, and a cam on the crank shaft to open all of the inlet valves, said cam adjustable on the crank

shaft to vary the time at which the inlet valves are closed during the compression strokes of the pistons.

10. In an internal combustion engine, the combination comprising a fixed shaft having a crank pin; a fuel chamber rotatably mounted on said shaft; a series of cylinders fixed thereto; pistons working in the respective cylinders; connecting rods to connect the pistons to the crank-pin of the shaft, said pistons rotating with the cylinders about the crank pin; spring-closed valves in the pistons to control the charge of fuel from the fuel chamber to the cylinders; a cam on the crank pin common to all of the piston valves; cam-following shoes; and rods slidably supported by the connecting rods and connected to the shoes to engage with and open the valves upon alternate revolutions of the cylinders to control the passage of fuel from the fuel chamber to the cylinders.

11. In an internal combustion engine, the combination comprising a fixed crank shaft; a fuel chamber rotatably mounted on said shaft; a series of cylinders connected thereto; pistons working in the respective cylinders; connecting rods to connect the pistons to the crank-pin of the shaft whereby said pistons rotate with the cylinders about the crank pin; spring-closed valves in the pistons; and a cam on the crank pin to open said valves upon alternate revolutions of the cylinders to control the passage of fuel from the fuel chamber to the cylinders; and means to adjust said cam on the crank pin at will to vary the time at which the valves are opened and closed during the reciprocation of the pistons to regulate the volume and compression of fuel in the cylinders.

12. In an internal combustion engine, the combination comprising a fixed crank shaft; a fuel chamber rotatably mounted on said shaft; a series of cylinders connected thereto; pistons working in the respective cylinders; connecting rods to connect the pistons to the crank-pin of the shaft, whereby said pistons rotate with the cylinders about the crank pin; spring closed valves in the pistons; and means to open said valves upon alternate revolutions of the cylinders to control the passage of fuel from the fuel chamber to the cylinders, comprising a cam common to all of said valves consisting of a stationary disk on the crank pin and having a raceway in the face thereof, tappets slidably mounted in the connecting rods to engage with the valves, and shoes connected to the tappets to engage in the cam raceway.

13. In an internal combustion engine, the combination comprising a fixed crank shaft; a fuel chamber rotatably mounted on said shaft; a series of cylinders connected thereto; pistons working in the respective cyl-

inders; connecting rods to connect the pistons to the crank-pin of the shaft, whereby said pistons rotate with the cylinders about the crank pin; spring closed valves in the pistons; means to open said valves upon alternate revolutions of the cylinders to control the passage of fuel from the fuel chamber to the cylinders, comprising a face-cam common to all the valves mounted on the crank pin, tappets slidably mounted in the connecting rods to engage with the valves, and shoes connected to the tappets to engage with the cam; and means to adjust said cam at will on the crank pin to vary the time at which the valves are opened and closed during the reciprocation of the pistons to regulate the volume and compression of fuel in the cylinders.

14. In an internal combustion engine, the combination of a fixed hollow crank shaft; a crank case rotatably mounted on said shaft, said case connected to the source of fuel supply through said shaft and constituting a fuel chamber; cylinders fixed to and rotatable with said case; pistons to work in the respective cylinders and connected to the crank pin of the shaft to rotate about the same; spring-closed valves in the pistons to control the passage of fuel from the fuel chamber to the cylinders, a cam on the crank pin of the shaft common to all of the piston valves; and means carried by the piston and crank connections operable by the cam to engage with and open the valves upon alternate reciprocations or revolutions of the pistons.

15. In an internal combustion engine, the combination of a fixed hollow crank shaft; a crank case rotatably mounted on said shaft, said case connected to the source of fuel supply through said shaft and constituting a fuel chamber; cylinders fixed to and rotatable with said case; pistons to work in the respective cylinders and connected to the crank pin of the shaft to rotate about the same; spring-closed valves in the pistons to control the passage of fuel from the fuel chamber to the cylinders; and a stationary cam on the crank pin of the shaft common to all of said valves to open said valves upon alternate reciprocations or revolutions of the pistons.

16. In an internal combustion engine, the combination of a fixed hollow crank shaft; a crank case rotatably mounted on said shaft, said case connected to the source of fuel supply through said shaft and constituting a fuel chamber; cylinders fixed to and rotatable with said case; pistons to work in the respective cylinders and connected to the crank pin of the shaft to rotate about the same; spring-closed valves in the pistons to control the passage of fuel from the fuel chamber to the cylinders; and a cam on the crank-pin of the shaft to open

said valves, said cam being adjustable about the crank pin to vary the time at which the valves are opened during the reciprocation of the pistons to regulate the volume and 5 compression of the fuel in the cylinders.

17. An internal combustion engine, comprising a rotatable fuel chamber; a series of cylinders fixed to said chamber to project radially therefrom; pistons working in the 10 cylinders; inlet valves in the pistons to control the passage of fuel from the fuel chamber to the cylinders; and a cam to control the operation of all of said valves, said cam being adjustable to vary the time at which 15 the valves are opened and closed during the reciprocation of the pistons.

18. In an internal combustion engine, the combination of a fixed crank shaft; a fuel chamber rotatably mounted on said shaft; 20 a series of cylinders connected thereto; pistons working in the respective cylinders; connecting rods to connect the pistons with the crank pin of the shaft, whereby said pistons rotate with the cylinders about the 25 crank pin; spring-closed valves in the pistons; and means to open said valves upon alternate revolutions of the cylinders to control the passage of fuel from the fuel chamber to the cylinders, comprising a face cam 30 stationary on the crank pin, and cam followers slidably mounted in the connecting rods.

19. In an internal combustion engine, the combination of a fixed crank shaft; a fuel 35 chamber rotatably mounted on said shaft; a series of cylinders connected thereto; pistons working in the respective cylinders; connecting rods to connect the pistons to the crank-pin of the shaft, whereby said pistons 40 rotate with the cylinders about the crank pin; spring-closed valves in the pistons; and means to open said valves to permit the passage of fuel from the fuel chamber to the cylinders, comprising a cam consisting of a 45 disk on the crank pin having a pair of concentric and intersecting grooves in the face thereof to constitute a raceway, tappets slidably mounted in the connecting rods and adapted to engage with the valves, and cam 50 followers connected to said rods to engage in the cam raceway, said cam followers during the latter portion of the exhausting stroke, the entire suction stroke and the initial portion of the compression strokes of 55 the pistons engaging in the outer groove of the raceway and so constructed as to be switched through the intersecting portion in the raceway to the inner groove and engage therein during the latter portion of the compression stroke, the entire power stroke and the initial portion of the exhausting stroke of the pistons; said outer groove having a raised portion for substantially 180 degrees and with which the cam followers engage 60 during the suction stroke of the pistons to

maintain the inlet valves open during such stroke.

20. In an internal combustion engine, the combination of a fixed crank shaft; a fuel chamber rotatably mounted on said shaft; a 70 series of cylinders connected thereto; pistons working in the respective cylinders; connecting rods to connect the pistons to the crank pin of the shaft, whereby said pistons rotate with the cylinders about the crank 75 pin; spring-closed valves in the pistons to control the passage of fuel from the fuel chamber to the cylinders; a stationary face cam on the crank pin; tappets slidably mounted in the connecting rods and adapted 80 to engage with the valves; and cam followers connected to said rods to engage with the cam; said cam being so constructed that during the suction stroke of the pistons or one-half revolution of the cylinders the 85 valves will be maintained open, and during the compression, power and exhausting strokes of the pistons or one and one-half revolutions of the cylinders the valves will be maintained closed. 90

21. In an internal combustion engine, the combination of a fixed crank shaft; a fuel chamber rotatably mounted on said shaft; a series of cylinders connected thereto; pistons working in the respective cylinders; connecting rods to connect the pistons to the crank pin of the shaft, whereby said pistons rotate with the cylinders about the crank pin; spring-closed valves in the pistons to control the passage of fuel from the fuel 100 chamber to the cylinders; a face cam on the crank pin; tappets slidably mounted in the connecting rods and adapted to engage with the valves; cam followers connected to said rods to engage with the cam; said cam being 105 so constructed that during the suction strokes of the pistons or one-half revolution of the cylinders movement will be imparted to the valve tappets through the cam followers to unseat and maintain the valves open, and during the compression, power and exhaust strokes of the pistons or one and one-half revolution of the cylinders no movement will be imparted to the valve tappets and the valves maintained closed; and means to 110 adjust the cam to vary the time at which the valves are opened and closed to regulate the volume and compression of fuel in the cylinders. 115

22. In an internal combustion engine, the combination of a crank shaft; a fuel chamber rotatably mounted on said shaft; a series of cylinders connected thereto; pistons working in the respective cylinders; connecting rods to connect the pistons to the crank pin of the shaft whereby said pistons rotate with the cylinders about the crank pin; removable valve seats in the pistons; puppet valves adapted to be seated in said seats; headed studs having a screw threaded engagement 120 125 130 135 140 145 150 155 160 165 170 175 180

with the puppet valves; coiled springs confined between the heads of the studs and the valve seats to maintain the valves closed; a stationary cam on the crank pin; and cam followers slidably mounted in the connecting rods to engage with and unseat the valves upon alternate reciprocations or revolutions of the pistons.

23. In an internal combustion engine, the combination of a crank shaft; a fuel chamber rotatably mounted on said shaft; a series of cylinders connected thereto; pistons working in the respective cylinders; connecting rods to connect the pistons to the crank pin of the shaft, whereby said pistons rotate with the cylinders about the crank pin; removable valve seats in the pistons; puppet valves adapted to be seated in said seats; headed studs having a screw threaded engagement with the puppet valves; coiled springs confined between the heads of the studs and the valve seats to maintain the valves closed; a stationary face cam on the crank pin; cam followers adapted to unseat the valves, comprising rods slidably mounted in the connecting rods and adapted to engage with the heads of the valve studs, said rods having a portion extending transversely to the movement thereof and projecting through slots in the connecting rods; shoes pivotally supported on said extending portion and engaging with the cam, said cam imparting movement to the cam followers to maintain the valves open during 180 degrees of revolution of the cylinders or during the suction strokes of the pistons and during the succeeding one and one-half revolution imparting no movement to the cam followers and the valves remaining closed.

40 24. In an internal combustion engine, the combination of a crank shaft; a fuel chamber rotatably mounted on said shaft; a series of cylinders connected thereto; pistons working in the respective cylinders; connecting rods to connect the pistons to the crank pin of the shaft, whereby said pistons rotate with the cylinders about the crank pin; removable valve seats in the pistons; puppet valves; headed studs having a screw threaded engagement with the puppet valves; coiled springs confined between the heads of the studs and the valve seats to maintain the valves closed; and means to unseat said valves to control the passage of fuel from the fuel chamber to the cylinders, comprising a cam consisting of a disk on the crank pin having a pair of concentric and intersecting grooves in the face thereof and constituting a raceway, rods slidably mounted in the connecting rods and adapted to engage with the heads of the valve studs, said rods having a portion extending transversely to the movement thereof and projecting through slots in the connecting rods, 65 shoes pivotally supported on said extending

portions, said shoes during one revolution of the cylinders engaging in the outer groove of the raceway, and maintaining the inlet valves open during 180 degrees of said revolution, and during the second revolution engaging in the inner groove of the raceway with the valves closed. 70

25. In an internal combustion engine, the combination of a hollow stationary crank shaft; a hollow casing rotatably mounted on said shaft and connected to the fuel supply through said shaft; a series of cylinders secured to said casing; pistons for the respective cylinders; connecting rods to connect the pistons to the crank pin of the shaft, 80 whereby the pistons rotate with the cylinders about said crank pin; inlet valves in the heads of the pistons to control the passage of fuel from the case to the cylinders; a cam on the crank pin; and cam followers 85 slidably mounted in the connecting rods and adapted to engage with the valves to operate the same.

26. In an internal combustion engine, the combination of a hollow stationary crank 90 shaft; a hollow casing rotatably mounted on said shaft and connected to the fuel supply through said shaft; a series of cylinders secured to said casing; pistons for the respective cylinders; connecting rods to connect 95 the pistons to the crank pin of the shaft, whereby the pistons rotate with the cylinders about said crank pin; inlet valves in the heads of the pistons to control the passage of fuel from the case to the cylinders; 100 an adjustable cam on the crank pin; cam followers slidably mounted in the connecting rods and adapted to engage with the valves to operate the same; and means to adjust the cam on the crank pin, comprising 105 a sleeve rotatably mounted in the hollow crank shaft, an actuating lever fixed to said sleeve and projecting through a slot in the shaft, and a link to connect said sleeve to the cam. 110

27. In an internal combustion engine, the combination of a crank shaft; a fuel chamber; a series of cylinders fixed to said chamber; pistons to work in the respective cylinders and connected to the crank of the shaft; inlet valves in the respective pistons to control the passage of fuel from the fuel chamber to the cylinders; a cam on the crank pin of the shaft common to all of the inlet valves; cam followers slidably carried by the 115 piston and crank connections adapted to engage with and open the valves upon alternate reciprocations of the pistons; spring closed exhaust valves in the heads of the cylinders; a cam fixed to the crank shaft; and cam followers connected to said exhaust valves and actuated by said latter valve to open said valves alternately with the opening of the valves in the pistons. 120 125

28. In an internal combustion engine, the 130

combination of a fixed hollow crank shaft; a hollow casing rotatably mounted on said shaft and communicating with the fuel supply therethrough; a series of cylinders fixed to said casing; pistons for the respective cylinders connected to the crank pin of the shaft; valves in the pistons to control the passage of fuel from the casing to the cylinders; an adjustable valve-operating cam 10 on the crank pin; exhaust valves in the cylinders, and a stationary cam on the crank shaft to operate said latter valves.

29. In an internal combustion engine, the combination of a fixed hollow shaft; a hollow casing rotatably mounted on said shaft and communicating with the fuel supply therethrough; a series of cylinders fixed to said casing; pistons for the respective cylinders; connecting rods to connect the pistons 15 to the crank pin of the shaft; spring closed valves in the pistons; a cam on the crank pin; cam followers carried by the connecting rods adapted to engage with and open the valves upon alternate reciprocations or 20 revolutions of the pistons; spring closed exhaust valves in the heads of the cylinders; a cam on the crank shaft; and cam followers connected to said latter valves to open the same alternately with the opening of 25 the piston valves.

30. In an internal combustion engine, the combination of a fixed hollow crank shaft; a fuel chamber rotatably mounted on said shaft and connected to the source of fuel 35 supply through said shaft; cylinders fixed to and rotatable with said chamber; pistons to work in the respective cylinders and connected to the crank pin of the shaft to rotate about the same; valves in the respective 40 pistons to control the passage of fuel from the fuel chamber to the cylinders; a valve operating cam common to all of the valves on the crank pin of the shaft to open said valves upon alternate reciprocations of 45 the pistons; spring-closed exhaust valves in the heads of the cylinders; and a cam on the crank shaft to open the exhaust valves upon alternate revolutions of the cylinders and alternately with the opening of the piston 50 valves.

31. In an internal combustion engine, the combination of a fixed hollow shaft having a crank; a fuel chamber rotatably mounted on said shaft and connected to the source of fuel supply through said shaft; cylinders fixed to and rotatable with said chamber; pistons to work in the respective cylinders and connected to the crank pin of the shaft to rotate about the same; spring-closed 55 valves in the respective pistons; a cam on the crank pin common to all of said valves to open the valves upon alternate revolutions of the cylinders to control the passage of fuel from the fuel chamber to the cylinders; spring-closed exhaust valves in the 60

heads of the cylinders; and means to open the exhaust valves upon alternate revolutions of the cylinders and alternately with the opening of the inlet valves, comprising a cam common to all of said valves fixed 70 to the crank shaft, levers carried by the cylinders and connected with the valves, slidably supported rods connected to the levers, and cam-followers connected to said rods and engaging with the cam.

32. A four cycle internal combustion engine, comprising in combination a crank shaft, a fuel chamber; a series of cylinders; pistons for the respective cylinders connected to the crank shaft; spring closed inlet valves in the respective pistons; a cam on the crank pin of the shaft; valve opening cam followers, said cam being so constructed as to actuate the cam followers to cause them to engage with and maintain the 80 inlet valves open during the suction stroke of the pistons; exhaust valves in the cylinders; a second cam on the crank shaft; and valve opening cam-followers, said latter cam being so constructed as to actuate the latter 85 cam followers to cause them to open and maintain said exhaust valves open during the exhaust stroke of the pistons.

33. An internal combustion engine, comprising in combination a fixed hollow crank shaft; a hollow casing rotatably mounted on said shaft and communicating with the fuel supply therethrough; a series of cylinders fixed to said casing; pistons for the respective cylinders connected to the crank pin of the shaft; spring closed inlet valves in the respective pistons; a cam on the crank pin common to all of said valves; valve opening cam followers, said cam being so constructed as to actuate the cam followers to cause them to engage with and maintain the valves open during 180 degrees of two revolutions of the cylinders; spring closed exhaust valves in the heads of the cylinders; a second cam on the crank shaft; and valve opening cam followers, said latter cam being so constructed as to actuate the latter cam followers to cause them to open and maintain said exhaust valves open during 180 degrees of two 100 revolutions of the pistons and alternately 105 with the opening of the inlet valves.

34. In an internal combustion engine, the combination of a crank shaft; a cylinder; a piston to work in the cylinder; a removable valve cage in the piston head; a valve, the stem of which is slidably mounted in the valve cage; a hanger connected to said valve cage within the piston; a connecting rod connected to said hanger and crank pin to connect the piston to the crank shaft; a cam 120 on the crank pin; and a cam follower slidably carried by the connecting rod to engage with the valve stem and open the valve upon alternate reciprocations of the piston.

35. In an internal combustion engine, the 125

- combination of a crank shaft; a cylinder; an exhaust valve in the cylinder; a piston to work in the cylinder; a removable valve seat in the piston head; a spring closed puppet 5 valve to engage in said seat; a stationary valve-operating face-cam on the crank pin; means to connect the piston to the crank shaft, comprising a pair of ball bearings on the crank pin, rings surrounding and secured to the bearings, a tubular member having a head consisting of laterally-projecting trunnions whereby it is connected to the valve seat, and at the other end connected to the bearing rings; and a cam-follower 10 slidably carried by the piston and crank connection to engage with the valve to unseat the same to control the passage of fuel to the cylinder.
36. In an internal combustion engine, the combination of a fixed crank shaft; a series of cylinders rotatable about said shaft; exhaust valves in the respective cylinders; pistons to work in the cylinders; removable valve seats in the piston heads; puppet valves seated in the valve seats; a cam common to all of said latter valves on the crank pin; and means to connect the pistons to the crank pin of the shaft, comprising hangers connected to the valve seats within the pistons, a pair of ball bearings on the crank pin, rings secured to and surrounding said bearings, each ring provided with an annular flange having a series of circumferentially disposed holes, one of the holes in each ring being polygonal in shape, rods, gudgeon pins whereby the rods are connected to the hangers, one of said rods provided with a pair of lateral polygonal shaped projections at the other end to engage in the polygonal holes in the bearing rings to secure said rod to the crank-pin, and gudgeon pins to engage in the holes in the bearing rings to pivotally connect the other rods of the crank pin.
- 45 37. In an internal combustion engine, the combination of a fixed crank shaft; a series of cylinders rotatable about said shaft; exhaust valves in the respective cylinders; pis-
- tons to work in the cylinders; removable valve seats in the piston heads; puppet valves seated in the valve seats; a cam common to all of said latter valves on the crank pin; and means to connect the pistons to the crank pin of the shaft, comprising a pair of ball bearings on the crank pin, rings surrounding said bearings, said rings having annular flange portions to embrace the sides of the bearings; rods connected to the flange portion of the rings, and gudgeon pins to connect the rods to the valve seats.
38. In an internal combustion engine, the combination of a fixed hollow crank shaft; a casing rotatable on said shaft and connected to the fuel supply therethrough; a series of cylinders fixed to and rotatable with the casing; exhaust valves in the respective cylinders; pistons to work in the cylinders; removable valve seats in the piston heads; puppet valves seated in the valve seats; a cam common to all of said latter valves on the crank pin of the shaft; means to connect the pistons to the crank shaft comprising hangers connected to the valve seats within the pistons, a pair of ball bearings on the crank pin, rings secured to and surrounding said bearings, each ring provided with an annular flange having a series of circumferentially disposed holes, one of the holes in each ring being polygonal in shape, rods, gudgeon pins whereby the rods are connected to the hangers, one of said rods provided with a pair of lateral polygonal shaped projections at the other end polygonal in shape to engage in the polygonal holes in the bearing rings to secure said rod to the crank-pin, and gudgeon pins to engage in the holes in the bearing rings to pivotally connect the other rods to the crank pin; and cam-fol-lowers slidably mounted in the hollow rods and adapted to engage with the valves in the piston heads to unseat the same.
